INVENTOR
EFFINGER E. WHIPPLE
BY Risley Lone
ATTORNEY'S.

UNITED STATES PATENT OFFICE.

EFFINGER E. WHIPPLE, OF UTICA, NEW YORK.

DESIGN FOR A CURVED SPRING HARROW-TOOTH.

SPECIFICATION forming part of Design No. 29,157, dated August 2, 1898.

Application filed June 27, 1898. Serial No. 684,624. Term of patent 14 years.

To all whom it may concern:

Be it known that I, EFFINGER E. WHIPPLE, a citizen of the United States, residing at Utica, county of Oneida, and State of New York, have invented and produced a new and original Design for a Curved Spring Harrow-Tooth, of which the following is a specification, reference being had to the accompanying drawings, forming a part thereof.

10 Figure 1 represents a top view of my spring curved harrow-tooth, it being a top view of Fig. 2. Fig. 2 represents an edge view of my spring curved harrow-tooth. Fig. 3 represents a view of Fig. 2, taken from the right of the same.

15 As shown in the drawings, the material features of my design consist in a curved

spring harrow-tooth of flat metal, the tooth having a curved portion and a straight portion, terminating at its butt in a bend, the 20 important features being that the tooth curves from its working point *a* backward, upward, and forward, terminating in a straight portion at its extremity *b*.

Having described my invention, what I 25 claim as new, and desire to secure by Letters Patent, is—

The design for the curved spring harrow-tooth as herein shown and described.

EFFINGER E. WHIPPLE.
